Primary Examiner — Katie Jane Stofko(57) **CLAIM**

The ornamental design for a recreational pit as shown and described.

DESCRIPTION

FIG. 1 is a perspective view of a recreational pit showing the claimed design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a bottom view thereof;

FIG. 7 is a top view thereof; and,

FIG. 8 is another perspective view thereof, shown in an environment of use.

Dot-dash broken line in FIGS. 1-3 and 8 are boundary lines that illustrate the bounds of the claimed design, and dash-dot broken lines in the figures illustrate portions of the recreational pit that form no part of the claimed design.

1 Claim, 8 Drawing Sheets(56)
